CHICKEN HOUSE

Fred M. Siptrott, Santa Rosa, Calif.

Application October 15, 1956, Serial No. 43,357

Term of patent 14 years

(Cl. D13—1)

Fig. 1

Fig. 2

Fig. 3

Fig. 1 is a perspective view of a chicken house showing my new design;

Fig. 2 is a side elevation, the opposite side being the same; and

Fig. 3 is an end elevation, the opposite end being the same.

I claim:

The ornamental design for a chicken house, substantially as shown.
